UNITED STATES PATENT OFFICE

111,762

DESIGN FOR A COAT

David Gerelick, New York, N. Y.

Application March 25, 1938, Serial No. 76,095

Term of patent 7 years

To all whom it may concern:

Be it known that I, David Gerelick, a citizen of the United States, residing at New York, in the county and State of New York, have invented a new, original, and ornamental Design for a Coat, of which the following is a specification, reference being had to the accompanying drawing, forming a part thereof, and in which:

Figure 1 is a front elevational view of a coat, showing my new design.

Figure 2 is a rear view of a coat.

The characteristic feature of the design resides in the specific stitching in association with the narrow band around the neck and along the front of the coat, as shown.

I claim:

The ornamental design for a coat, as shown and described.

DAVID GERELICK.
